UNITED STATES PATENT OFFICE.

JOHANNES CRONING, OF HAMBURG, GERMANY, ASSIGNOR, BY MESNE ASSIGNMENTS,
TO CROWN LOCK COMPANY, A CORPORATION OF DELAWARE.

METHOD OF ADJUSTING LOCKING CYLINDERS.

Application filed June 3, 1925, Serial No. 34,652, and in Germany September 30, 1924.

The present invention relates to a novel and practical method of adjusting the locking pins carried by the locking plugs of pin tumbler cylinder locks; and the object 5 of the invention is to provide a cheap and effective method whereby the plug is made movable relative to its surrounding casing only by the particular key used in the adjustment.

10 The form of cylinder locks in connection with which the invention has been developed and to which it is particularly applicable, is illustrated in the accompanying drawing wherein Fig. 1 shows in section the plug with the key in the keyway, partly turned down, Fig. 2 shows a cross-section of Fig. 1, and Fig. 3 shows a cross-section corresponding to Fig. 2, but of the completed operation. Such plugs *e* comprise a series 20 of alined holes constituting sleeves for the pins *d* which are provided with lateral projections *c* guided in alined holes *b* having a spring *f* on one side of the lateral projection *c* and a keyway on the other side thereof. The plugs are inserted in a round hole in a surrounding member, of the diameter of the finished plug, which is provided with recesses to receive projecting ends of the pins *d*, so that movement of the plug relative to the surrounding member in one or 30 more directions is prevented by the engagement of the pins while the ends thereof project beyond the circumference of the plug. The plug is freed for movement relative to the surrounding member by moving each of the pins so that its ends are within the circumference of the plug; and this is accomplished by a key which moves the pins. To make the plug movable relative to the 35 surrounding member only by a particular key, keys are made which differ from each other in the contour of the portions engaging the pins. A particular key is then inserted in the keyway and the ends of the 40 pins cut down to the cylinder so that all the pins are within the circumference of the plug while the pins are engaged by that particular key, with the result that ends of the pins project from the circumference of 45 the plug when that particular key is with- drawn or any different key inserted. The locking pins are thus adjusted to the particular key. The method used hitherto consisted in inserting the locking pins in the finished turned plug and whilst holding the 55 plug stationary filing them down by hand to the peripheral surface of the plug. This method, however, is tedious and is not always entirely accurate by reason of the hand work. The difficulty in securing accuracy 60 by this method is greatly increased by the fact that the pins are engaged by the springs *f* which yield to such an extent as to jeopardize the accuracy which is important in locks of this kind. The method according 65 to the invention is considerably simpler and cheaper and precision work is obtained.

5 The method of the invention the plug blank is made of somewhat larger diameter than the opening into which it is to be fitted. 70 The locking pins are then inserted and the key is introduced into the keyway of the plug blank whereby the locking pins are arranged in the position which they assume in the opened position of the lock. The whole 75 closing cylinder with the locking pins is then turned down in one operation to the extent required to enable it to be fitted into the hollow cylinder by rotating it rapidly. The plug and the pins are thus turned down 80 to the desired size, and since the turning tools exert pressure on the pins in one direction and cut them with the plug, an accurate adjustment results.

In order to entirely prevent the spring 85 actuated locking pins from yielding these may be locked before the turning operation by means of shellac or the like and are again released after the turning operation.

Having thus described my invention what 90 I claim as new and desire to secure by Letters Patent is:—

1. A method of adjusting the locking pins of cylinder locks to a particular key, comprising inserting the pins in a plug blank of 95 larger diameter than the finished plug, inserting the key in the keyway of the plug to move the pins to their position in the unlocked lock and rapidly rotating the plug blank in contact with tools to turn down the 100

plug blank and pin ends to the diameter of the finished plug.

2. A method of adjusting the locking pins of cylinder locks to a particular key, comprising inserting the pins and key in the plug so that the pins are in the position they occupy when the lock is unlocked, securing

the pins by shellac and removing the portion of the pins projecting beyond the circumference of the finished plug.

In testimony whereof I have affixed my signature.

10

JOHANNES CRONING.
